COMBINED POLE LAMP AND ANTENNA FOR TELEVISIONS OR THE LIKE

Roger Mark Singer, New York, N.Y., assignor to Snyder
Manufacturing Company, Philadelphia, Pa., a corpora-
tion of Pennsylvania

Filed Nov. 24, 1961, Ser. No. 67,692

Term of patent 14 years

(Cl. D48—20)

FIG. 1 is a side elevation of a combined pole lamp and antenna for televisions or the like showing my new design;

FIG. 2 is a rear elevation thereof with the antenna extended and in an alternate adjustable position;

FIG. 3 is a front elevation thereof with the antenna extended and in an alternate adjustable position;

FIG. 4 is an enlarged fragmentary perspective with the shade and handle in an alternate adjustable position; and

FIG. 5 is an enlarged fragmentary perspective view showing the rotatable dial and knob of the combined pole lamp and antenna.

I claim:

The ornamental design for a combined pole lamp and antenna for televisions or the like, substantially as shown and described.
